UNITED STATES PATENT OFFICE.

WILLIAM C. AUGENSTEIN, OF CHICAGO, ILLINOIS, ASSIGNOR TO VESTA BATTERY CORPORATION, A CORPORATION OF ILLINOIS.

DESIGN FOR A LAMP CASING OR SIMILAR ARTICLE.

60,598.

Specification for Design.

Patented Mar. 14, 1922.

Application filed April 27, 1921. Serial No. 465,000. Term of patent 3½ years.

To all whom it may concern:

Be it known that I, WILLIAM C. AUGENSTEIN, a citizen of the United States, and residing in the city of Chicago, county of Cook, and State of Illinois, have invented a new, original, and ornamental Design for Lamp Casings and Similar Articles, of which the following is the specification, reference being had to the accompanying drawings, forming a part thereof.

In the drawings:

Figure 1 is a perspective view of a lamp

casing illustrating the design embodying my invention.

Figure 2 is the rear elevation thereof.

Figure 3 is a bottom view thereof.

I claim:

The ornamental design for a lamp casing or similar device, as shown.

WILLIAM C. AUGENSTEIN.
